WASH TANK

Rudolph J. Anschicks, Chicago, Ill., assignor to
Protectoseal Company of America, Inc., Chi-
cago, Ill., a corporation of Illinois

Application December 7, 1938, Serial No. 244,376

4 Claims. (Cl. 220—89)

The invention relates to wash tanks or receptacles, and more particularly it relates to tanks or receptacles for inflammable or volatile liquids in which articles may be dipped or submerged and thereby subjected to the cleansing properties of the liquids.

This application is a continuation-in-part of my co-pending application Serial No. 180,599, filed December 18, 1937, and issued under date of April 25, 1939, as Patent No. 2,155,464 for a wash tank provided with a cover adapted to prevent evaporation and accidental ignition of the contents of the tank when the cover is closed.

More particularly the invention consists in the provision of novel means for supporting the cover in open position to permit access to the tank for insertion and removal of articles to be cleaned by immersion in the contents of the tank, the open position of the cover being such that it closes by gravity in the absence of the support afforded by such means.

The invention has among its objects the provision of novel means operatively related to the tank and cover whereby movement of the cover to open position causes said means to take a position wherein the cover is supported thereby in open position, said means being yieldable to permit the cover to close by exerting pressure on the cover, said means being also yieldable as a result of ignition of the tank contents to permit the cover to close by its own weight and thereby immediately terminate combustion inside of the tank.

A further object of the invention is to provide a tank or receptacle of the kind described having improved means automatically operable to quickly stop combustion of the fluid contents of the tank in the event of ignition by accident or otherwise.

Another object of the invention is to provide a tank or washing device of the kind described with a removable drainage basket for holding articles which are to be immersed in the volatile liquid and improved means for supporting said basket above the liquid.

A still further object of the invention is the production of devices of the kind described which are convenient, safe, durable and satisfactory for use wherever found applicable.

Many other objects and advantages of the construction herein shown and described will be obvious to those skilled in the art from the disclosure herein given.

To this end, my invention consists in the novel construction, arrangement and combination of

parts herein shown and described and more particularly pointed out in the claims.

In the drawing, wherein like reference characters indicate like or corresponding parts:

Fig. 1 is an elevational and partial sectional view of a tank having a hinged cover and a basket embodying the principles of the invention, the basket being shown supported in the upper end of the tank and the cover being shown in open position;

Fig. 2 is a view of a portion of the tank taken along the line 2—2 of Fig. 1; and

Fig. 3 is a view along the line 3—3 of Fig. 1.

Referring now more particularly to the drawing, the numerals 10 and 11 designate respectively a wash tank and a screen basket adapted as a receptacle for articles to be cleaned. The tank 10 is shown as cylindrical and is provided with a hinged cover 12 and a pair of bars forming handles 13 suitably projecting from and positioned on opposite sides of the tank. The cover 12 when open is slightly inclined to the vertical and correspondingly projects over the top of the tank.

25 The side and bottom walls of the basket 11 are provided with a plurality of apertures 14 to permit entrance of the tank liquid in which the basket is submerged or partially submerged when resting on the bottom of the tank. The basket

30 11 has a pair of oppositely positioned outside handles 15 shown as respectively overlapping and resting upon supporting and guide elements 16, the elements being equally spaced from the hinged connection of the cover 12 and suitably fastened

35 to the opposite side walls of the tank 10. A pair of bars 17, positioned inside of and fastened to the basket 11 by welding or any other suitable means, provides additional handles by means of which the basket may be conveniently lifted from the position shown and be otherwise manipulated.

40 A pair of vertically extending bars 18 oppositely positioned in the tank 10 and preferably equally spaced from the supporting elements 16 have their ends fastened to the tank by welding or the like. The middle portions of the bars 18 project inwardly to provide additional spacers for the basket 11, and the end portions of the bars are inclined to provide guides for the basket during its insertion and removal from the tank 10. The

45 described arrangement of the supporting elements 16 and bars 18 enables the basket 11 to be easily inserted in and removed from the tank notwithstanding the open cover 12 projects over the top of the tank.

In practice, the tank 10 is partially filled with

volatile cleaning liquid such as naphtha or the like and the basket 11, containing the article or articles to be cleaned, is lowered to the bottom of the tank with the handles 15 positioned intermediate the bars 16 and the supporting elements 18. Upon completion of the dipping or submerging of the articles in the tank liquid, the basket is lifted and suspended in the upper end of the tank by engaging the handles 15 with the elements 16 to permit drainage of the basket and the articles contained therein through the apertures 14.

The tank fluid being volatile and exposed to accidental ignition when the cover 12 is open, means is provided whereby such ignition permits the cover to close by gravity and stop all combustion within the tank. An assembly of operatively related elements carried by the cover 12 and generally designated by the numeral 20 is provided to support the cover in open position in contact with a stop member 21, said open position of the cover as above stated being such that it tends to close by gravity.

The cover 12 is hingedly connected to the tank 10 by a pivot 19 extending through cooperating hinge members 22 and 23 respectively fastened to the cover and to the tank. The cover supporting means 20 includes a relatively thin elongated bar or support member 24 normally adapted to hold the cover 12 in open position when the cover is in engagement with the member 21. The member 24 extends along the inside face of the cover 12 and between said face and a pair of guide members 25 mounted on the cover. One end of the member 24 projects inwardly and is apertured to receive a bolt 26 having an end curved to provide a hook or open eye 27. The other end of the member 24 is turned laterally to form spaced apart folds or loops 28 and 29, as shown, and with its extreme end portion slightly curved and engaging the rim 30 of the tank 10 when the cover 12 is open. The cover supporting means 20 also includes a stud 31 suitably mounted on one of the guide members 25 and extending through an aperture 32 provided in one end of a fusible link 33. The apertured end of the link 33 is maintained on the stud 31 by a pin 34 and its other end is connected with the bolt 26 by inserting the hook 27 of the bolt through an aperture 35 provided by the link. The end of the member 24, providing the loops 28 and 29, is normally held in adjustable bearing contact with the rim 30 of the tank 10 by means of a nut 36 threaded on the bolt 26 to engage the inwardly projecting apertured end of the member through which the bolt extends the link 33 being tensioned by such contact. The curvature and relative inclination and positions of the loops 28 and 29 are such that the member 24 maintains the cover 12 in the position shown and the member is thereby yieldable by sliding of the loop 29 over the rim 30 or by bending of the loops 28 and 29 or by both to permit the cover to close by manual pressure thereon or by manipulation of the member itself. In thus closing the cover 12, the extreme tank engaging end portion of the loop 29 rides over and disengages the rim 30 and likewise in lifting the cover to open position, the loop 29 disengages the rim and is moved to the position shown wherein it adapts the member 24 to support the cover.

In case of the ignition of the liquid contents of the tank 10 or of the gases emanating therefrom when the cover 12 is open, the heat of combustion will quickly fuse the link 33 to a condi-

tion wherein it will yield by elongation under its tensile stress and permit the member 24 to move longitudinally upwardly along the cover 12 to a position wherein the loop 29 disengages or is slideable over the rim 30 of the tank 10 and permits the cover to close by gravity and thereby stop combustion.

Thus, it will be seen that the invention provides improvements in wash tanks of the kind described including means for supporting a basket while draining, and in improvements in devices for holding the tank cover in an open position wherein it tends to close by gravity, said devices permitting the cover to be manually opened and closed and being also automatically operable, to permit the cover to close by gravity as a result of the ignition of the fluid contents of the tank.

Having thus described my invention, it is obvious that various immaterial modifications may be made in the same without departing from the spirit of my invention; hence, I do not wish to be understood as limiting myself to the exact form, construction, arrangement and combination of parts herein shown and described or uses mentioned.

What I claim as new and desire to secure by Letters Patent is:

1. The combination in a wash tank of the kind described having an opening and a cover adapted to be moved downwardly to close the opening and to be moved upwardly into an open position wherein it tends to close by gravity, of a support member mounted on and automatically operable by movement of the cover from closed to open position to engage the tank and maintain the cover against closure by gravity when in said open position, said support member being yieldable to disengage the tank upon the application of force tending to move the cover from open to closed position, and an elongated fusible element operatively related to and subjected to a tensile pull longitudinally by said operative relation adapted to maintain the support member against movement relative to the cover when in open position, said element being mounted on the inner side of the cover and when fused being adapted to yield by elongation and permit the support member to move relative to the cover and to thereby operatively disengage the tank and allow the cover to close by gravity.

2. The combination in a wash tank of the kind described having an opening and a hinged cover for said opening adapted to be swung from closed to open position and vice versa through an arc of less than ninety degrees, of a bar mounted on the cover, one end of said bar being turned to provide a resilient lateral extension adapted to engage the rim of the tank and support the cover upon its movement to open position, said lateral extension being yieldable to disengage the tank upon the application of force to the cover tending to swing it from open to closed position, and a fusible element operatively related to and normally adapted to maintain the bar against longitudinal movement relative to the cover, said element being mounted on the inner side of the cover and when fused being yieldable to permit longitudinal movement of the bar and thereby to allow the cover to close by gravity.

3. The combination in a wash tank of the kind described having an opening and a hinged cover for said opening adapted to be swung from closed to open position and vice versa through an arc

of less than ninety degrees, of a bar mounted on the cover, one end of said bar being arranged to provide a plurality of resilient sinuously arranged lateral extensions with the end extension adapted to engage the rim of the tank whereby the bar provides a support for the cover upon its movement to open position, said lateral extensions being yieldable to disengage the bar from the tank upon the application of force to the cover tending to swing it from open to closed position, and a fusible element operatively related to and normally adapted to maintain the bar against longitudinal movement relative to the cover, said element being mounted on the cover and when fused being yieldable to permit longitudinal movement of the bar and thereby to allow the cover to close by gravity.

4. A wash tank of the kind described having a hinged cover, a member adapted to stop the

cover at an open position wherein it will close by gravity, an elongated member extending along the cover, means connecting the cover with and preventing longitudinal movement of the elongated member relative to the cover, said elongated member operatively engaging the tank to normally hold the cover in said open position, said elongated member being yieldable laterally to permit manual actuation of the cover from open to closed position and vice versa, said means including an element positioned inside of the cover, said element being fusible upon exposure to heat generated by initial combustion of the volatile fluid contents of the tank, said element when fused releasing said elongated member to permit longitudinal movement thereof relative to the cover and the cover thereby to be closed by gravity.

RUDOLPH J. ANSCHICKS.
